UNITED STATES PATENT OFFICE.

ANTHONY J. PRENOSIL, OF DWIGHT, NEBRASKA, ASSIGNOR OF ONE-HALF TO JOHN F. KRENK, OF DWIGHT, NEBRASKA.

KNIFE-SHARPENER.

1,178,099.

Specification of Letters Patent.

Patented Apr. 4, 1916.

Application filed January 29, 1915. Serial No. 5,102.

To all whom it may concern:

Be it known that I, ANTHONY J. PRENOSIL, a citizen of the United States, residing at Dwight, in the county of Butler and State 5 of Nebraska, have invented certain new and useful Improvements in Knife-Sharpener, of which the following is a specification.

My invention relates to sharpening devices and more particularly to a device for 10 sharpening knives or other cutlery.

The primary object of this invention resides in the provision of a knife sharpener embodying spaced resilient arms for supporting abrading means on the adjacent 15 inner faces thereof, the arms being bent outwardly above the abrading means to provide finger engaging portions whereby when these portions are engaged by the fingers of the operator and pressed together, the friction 20 between the abrading means and a knife or other implement movable therebetween, will be consequently increased.

A still further object of my invention resides in the provision of a device of the 25 character described that is simple in construction, efficient in operation and one that can be manufactured and placed on the market at a minimum cost.

Other objects as well as the nature, character 30 and scope of my invention will be more readily understood from the following description taken in connection with the accompanying drawings and pointed out in the claim forming a part of this 35 specification.

In the drawings: Figure 1 represents a perspective view of my invention, the dotted lines showing a knife associated therewith. Fig. 2 represents a longitudinal, sectional 40 view of my invention. Fig. 3 represents a transverse sectional view taken on the line 3—3 of Fig. 2 in the direction in which the arrow points.

Referring more particularly to the drawings in which similar reference numerals 45 designate like or corresponding parts throughout the different views, I provide my improved supporting means or holder which in this instance is formed preferably from a single strip of sheet metal bent intermediate 50 its ends into a substantially U-shaped configuration, the vertex being arranged into a substantially cylindrical formation to provide a bow spring 1, the arms 2 and 3 of the 55 holder extending from the spring being ar-

ranged in spaced parallel relation with each other and because of the cylindrical construction of the spring the arms are made resilient. The terminals of the arms are bent outwardly in opposite directions to 60 each other as at 4 to provide finger engaging portions 5 for a purpose to be hereinafter referred to.

In order to provide a suitable means for 65 sharpening the blade of a knife or other piece of cutlery I have provided oblong file blocks 6 and have removably secured the said blocks to the inner surface of the arms by means of screws or like fastening devices 70 which pass through the opening 8 in the arms and engage the rear surfaces of the blocks 6. Attention is directed to the peculiar manner in which the blocks are arranged between the arms. It will be noted that the 70 inner ends thereof are arranged in substantial alignment with the point of juncture of the arms with the spring and the outer ends extend slightly above the plane of the outer edges of the finger engaging portions 5. The finger engaging portions 5 are bent outwardly at the points 4, the said points being positioned at a point substantially intermediate the inner and outer ends of the blocks. By this arrangement an equal 75 amount of pressure may at all times be arranged on the blocks while a knife or other piece of cutlery is being sharpened. Furthermore due to the resiliency of the material from which the arms are formed the finger engaging portions may be pressed toward 80 each other when it is desired to increase the friction between the blocks at the outer ends thereof. The blocks have their extreme outer ends beveled as at 9 thus affording a suitable surface whereby the fingers of the user, not shown, are adapted to engage should a strong pressure on the block be desired. A set screw eye 10 is removably 85 engaged in the spring and constitutes a suitable means for supporting the holder on a nail or the like, not shown.

The operation of my invention is as follows: A knife or other piece of cutlery is placed between the spaced surfaces of the abrading blocks 6 and slid transversely 90 therebetween, the holder being held in one hand of the operator, not shown, during this operation. If it is desired to increase the friction between the abrasive blocks, the 95 fingers of the hand which engage the holder 100

are engaged upon the finger portions 5 and pressed together to consequently cause the blocks to more firmly engage the sides of the knife. Should it be desired to replace the blocks 6 when they have become worn it is only necessary to remove the screws 7 and replace new blocks, the operation being obvious.

Although I have shown and described the preferred embodiment of my invention I do not wish to limit myself to the exact structure shown, however, particular attention is directed to the peculiar arrangement on the finger portions 5 in the manner in which they coöperate with the abrading blocks for producing an efficient means for governing the friction between the device when in operation.

From the above description taken in connection with the accompanying drawings, it can easily be seen that I have provided a device that is simple in construction, containing but a few simple parts that can be cheaply manufactured and assembled and when assembled can be placed upon the market and sold at a minimum cost.

It will be understood that the above description and accompanying drawings comprehend only the general embodiment of my invention and that various minor

changes in detail of construction, proportion and arrangement of the parts may be made within the scope of the appended claim and without sacrificing any of the advantages of my invention.

35

Having thus fully described my invention, what I claim as new and desire to secure by Letters Patent, is:—

A knife sharpener formed from a single strip of sheet metal including a pair of parallel spaced resilient supporting arms, formed by bending the metal upon itself, a bow spring provided at the bend, a file block associated with the inner surfaces of each of the arms, fastening devices for removably holding the blocks on the arms, finger engaging portions formed by bending the outer ends of the arms outwardly from a point substantially intermediate the ends of the block and engageable by the fingers of the operator for pressing the blocks together for consequently increasing the friction of the blocks with a tool.

In testimony whereof I affix my signature in presence of two witnesses.

ANTHONY J. PRENOSIL.
